[57] CLAIM

The ornamental design for a water closet or the like, as
shown and described.

DESCRIPTION

FIG. 1 is a perspective view, taken from the top, front
and left side of a water closet or the like, embodying my
new design;
FIG. 2 is a left side elevational view thereof;
FIG. 3 is a right side elevational view thereof;
FIG. 4 is a top plan view thereof;
FIG. 5 is a front elevational view thereof;
FIG. 6 is a rear elevational view thereof; and
FIG. 7 is a bottom plan view thereof.
The broken line representation of an opening in FIGS.
1, 2, and 5 are for purposes of illustration only.
